UNITED STATES PATENT OFFICE.

HARALD J. VENNES, OF MONTREAL, QUEBEC, CANADA, ASSIGNOR TO WESTERN ELECTRIC COMPANY, INCORPORATED, OF NEW YORK, N. Y., A CORPORATION OF NEW YORK.

CURRENT-WAVE TRANSMISSION.

Application filed May 26, 1919, Serial No. 299,749. Renewed April 15, 1925.

To all whom it may concern:

Be it known that I, HARALD J. VENNES, a citizen of the United States, residing at Montreal, in the Province of Quebec, Dominion of Canada, have invented certain new and useful Improvements in Current-Wave Transmission, of which the following is a full, clear, concise, and exact description.

10 This invention relates to transmission of currents of different frequencies, and more particularly to any system in which currents of different frequencies are to be impressed at the same time independently upon the same circuit, such as, for instance, in multiplex signaling. The invention comprises a simplified circuit arrangement for associating a number of different current sources with a common 15 line, whereby currents having different characteristics are conveyed from said sources to said line without interference and in an efficient manner.

Heretofore, for example, as indicated in 20 U. S. Patents No. 1,313,483 to R. A. Heising, issued August 19, 1919, and No. 1,445,141 to B. W. Kendall, issued February 13, 1923, it has been the practice to connect current generators of different 25 frequency to a common line through an amplifier for each such generator and a selective circuit between each amplifier and the line. This necessitates the use of as many amplifiers as there are generators and means that 30 each selective circuit must carry the amplified current, and each amplifier must provide for the losses in the selective circuit due to the amplified currents.

According to the invention one amplifier 35 suffices for all the generators and this results in considerable saving of amplifiers, especially in systems carrying, for example, 30 or 40 transmissions in each direction. Also in the system according to the invention 40 the selective circuits carry the generated but not the amplified currents, so that the losses incurred in these portions of the circuit are considerably reduced.

In the drawing, line 1 may be a multiplex transmission line upon which currents 45 of different frequencies are to be impressed from a series of generators of which O_1 and O_2 are shown. By the conjugate arrangement comprising line coils 2 and 3 and the 50 line balance 4, as shown, the line may be

adapted for two-way transmission of currents, so that incoming currents may be received by suitable receivers of which one, indicated R, is shown.

The generators such as O_1 and O_2 may 60 be of any suitable type for producing oscillations of the desired frequencies. Each of the ones shown is of the thermionic type having an oscillatory input circuit 5 into which energy is fed from the output circuit 6 by means of mutual inductance between the input and output circuits. The space-current circuit for the oscillator from the source 6 includes a normally open contact 7 which may be controlled by a relay 8 in 70 the circuit of which a key 9 is shown, so that with key 9 closed the space-current is supplied to the oscillator and sustained oscillations of definite frequency are set up in the oscillatory or filtering circuit 10 to 75 which coil 11 in the output circuit of generator O_1 is coupled. Generator O_2 by a similar coil 12 delivers current to tuned or filtering circuit 13 of a different frequency 80 from the current produced in circuit 10 by generator O_1 . Oscillatory circuits 10 and 13 are tuned to their respective generator frequencies which as stated are different so that energy from generator O_1 , for example, 85 produces maximum oscillations in circuit 10 but has negligible effect on oscillatory circuit 13. By this provision the output energy of either generator is prevented from reacting upon the other and current of each 90 frequency is impressed across the terminals of resistance 14. This resistance acts as a potentiometer along which the taps 15, 16 may be adjusted to regulate the voltage impressed upon the respective grids of amplifier 17. It is the function of amplifier 17 95 to amplify non-selectively all the currents impressed upon it. An amplifier capable of handling currents of considerable frequency range is necessary for this purpose, and it must possess a substantially linear characteristic throughout the operating range so 100 that currents of the different frequencies shall not modulate one another. The particular type shown is that in which two discharge devices 18 and 19 are so associated that a given impressed potential across the input resistance 14 causes at any instant, equal and opposite variations in the grid potential of the respective grids of the two 105 discharge devices, and is known as the 110

"push-pull" type. As a result of the complementary impedance variations thus caused in the two discharge devices, amplified current flows in the output coil 20 and is impressed 5 through coil 21 upon the line 1.

Incoming currents in line 1 produce current flow through coils 22 to the input of the two-stage amplifier A_1 , A_2 , which is also adapted to pass currents of considerable frequency range without interference 10 between the currents of different frequencies, and each stage of which may be of the same general type as amplifier 17. By means of the conjugate arrangement for 15 connecting to the line 1, currents from amplifier 17 do not reach amplifier A_1 as is well-known in the art. From the output coupling 23 of the second-stage amplifier A_2 , the amplified currents pass into a circuit 20 comprising as many tuned circuit branches 24, 25 as there are transmissions to be separately received and to each such tuned-circuit branch may be coupled a detector D for rendering the signal receivable 25 by relay 26, which may control a local circuit as indicated or if desired a telephone receiver or other suitable receiver may be used.

While the particular generators, transmitters and receivers illustrated and described are for telegraph transmission, it is obvious that the invention is adaptable generally to transmission of currents of different frequencies for the selective operation 30 of any desired mechanism, an example being carrier currents, which may be modulated in accordance with any desired kind of signal, for instance, as by speech by providing the appropriate kind of transmitter 35 and receiver, such, for instance, as a microphone and a telephone receiver. It is obvious also that transmitting and receiving antennæ may be substituted for the line.

While the invention has been illustrated 40 and described with reference to a particular system, it is to be understood that it is not to be limited either to the specific system or circuit arrangements as a whole, or to the particular details, but only by the 45 scope of the appended claims.

What is claimed is:

1. In a system of current transmission, a line for simultaneously conveying currents of different frequencies, a plurality of means 45 for producing currents of different frequencies for said line, a selective circuit associated with each of said means, a collecting circuit common to said plurality of means for receiving currents from the individual selective circuits, and an amplifier having its input coupled to said collecting circuit and its output coupled to said line for amplifying said currents of different frequencies and for impressing them upon said line.
- 60 2. In a signaling system, a transmission

line for simultaneously conveying a plurality of different currents forming communication channels thereover, current sources for said channels, filtering circuits coupled to said current sources, a collecting 70 circuit common to said sources for receiving the currents from said filtering circuits, and an amplifier having its input coupled to said collecting circuit and its output coupled to said line for amplifying said currents of different frequencies and for impressing them upon said line.

3. In a signaling system, a transmission line for simultaneously conveying currents of different frequencies, terminal apparatus for said line including transmitters of 80 said frequencies, a common amplifier between said transmitters and said line, and frequency selective circuits interposed between said amplifier and said transmitters. 85

4. A line for the simultaneous transmission of currents in both directions thereover, a plurality of receiving circuits, a plurality of transmitting circuits, a plurality of sources of current for said transmitting 90 circuits, means at a terminal station to keep the transmitted currents out of the local receiving circuits and the received currents out of the transmitting circuits, and an amplifier common to a plurality of said transmitting circuits. 95

5. In a system of current transmission, a line for simultaneously conveying currents of different frequencies, a plurality of current sources of different frequencies for 100 said line, an amplifier common to said current sources for amplifying said currents of different frequencies and for impressing them upon said line, and means interposed between said amplifier and each of said sources for preventing interaction among 105 said sources.

6. In a signaling system, a common transmission line, sources of current of different frequencies associated with said line, a common unilateral amplifier connected between 110 said sources and said line, and tuned transmitting circuits connected between said amplifier and said sources.

7. A multiplex signal receiving system 115 comprising a transmission medium, means for amplifying carrier waves of different frequencies each modulated in accordance with telegraph signals incoming simultaneously over said transmission medium, a selective circuit passing certain of the amplified waves to the exclusion of other waves, a rectifier actuated by current passing through said selective circuit, and a translating device energized by rectified current from said rectifier. 120

8. A line for the simultaneous transmission of currents in both directions thereover, a net circuit for balancing the impedance of 125 said line for the transmitted currents, re- 130

ceiving circuits, transmitting circuits, means for conjugately associating said receiving and transmitting circuits with each other and with said line and net, a plurality of sources 5 of current of different frequencies for said transmitting circuits and an amplifier common to a plurality of said transmitting circuits.

9. In a system of current transmission, a 10 transmission medium, a plurality of sources of currents of different frequencies, a selective circuit associated with each of said sources, a receiving circuit, a net circuit for balancing the electrical characteristics of 15 said medium, means for conjugately associating said receiving and transmitting circuits with each other and with said medium and net, and an amplifier common to said selective circuits and said plurality of sources for amplifying said currents of different frequencies and for impressing them upon said conjugate connecting means.

10. In a signaling system, a transmission line, a plurality of individually tuned transmitting circuits associated therewith, a receiving circuit, a net circuit for balancing the electrical characteristics of said line for the frequencies corresponding to the individual tuned circuits, means for conjugately associating said receiving and transmitting circuits with each other and with said line and net, and means common to a plurality of said transmitting circuits to prevent reaction between said line and said tuned transmitting circuits due to the reactive characteristics of said line and said circuits, said means comprising a space discharge amplifier.

11. A line for the simultaneous transmission of currents in both directions thereover, a plurality of receiving circuits, a plurality of transmitting circuits, a plurality of sources of current for said transmitting circuits, a conjugate arrangement at a terminal station to keep the transmitted currents out of the local receiving circuits and the receiving currents out of the local transmitting circuits and an electron discharge amplifier of the push-pull type common to a 50 plurality of said transmitting circuits.

12. In a wave transmission system, a transmitting medium, transmitting wave sources of different frequencies, a receiving

circuit, a net circuit for balancing the electrical characteristics of said medium, means 55 for conjugately associating said receiving and transmitting circuits with each other and with said medium and net, and a common means for amplifying simultaneously the waves from said sources and impressing 60 the amplified energies upon said conjugate connecting means, said amplifying means comprising a balanced discharge tube amplifier circuit having a resistance connected across its input terminals, individual selective circuits for said wave sources and connections from said resistance to said selective circuits in series with one another as a group.

13. In a signaling system, a transmission 70 line, a plurality of individually tuned transmitting circuits associated therewith, and means to prevent reaction between said line and said tuned transmitting circuits due to the reactive characteristics of said line and 75 said circuits, said means comprising an amplifier of the push-pull type.

14. A line for the simultaneous transmission of currents in both directions thereover, a plurality of receiving circuits, a plurality 80 of transmitting circuits, a plurality of sources of currents for said transmitting circuits, means at a terminal station to keep the transmitted currents out of the local receiving circuits and the received currents 85 out of the transmitting circuits, and an electron-discharge amplifier of the push-pull type common to a plurality of said transmitting circuits.

15. In a wave transmission system, a 90 transmitting medium, transmitting wave sources of different frequencies, and a common means for amplifying simultaneously the waves from said sources and impressing the amplified energies upon said medium, 95 said means comprising a balanced discharge tube amplifier circuit having an ohmic resistance connected across its input terminals, individual selective circuits for said wave sources and connections from said resistance to said selective circuits in series with one another as a group.

In witness whereof, I hereunto subscribe my name this 15th day of May A. D., 1919.

HARALD J. VENNES.
